UNITED STATES PATENT OFFICE.

MILLER REESE HUTCHISON, OF ORANGE, NEW JERSEY, ASSIGNOR TO HUTCHISON THRIFT CORPORATION, OF NEW YORK, N. Y., A CORPORATION OF DELAWARE.

GATE AND BARRIER CONTROL MECHANISM.

Application filed June 15, 1922. Serial No. 568,536.

To all whom it may concern:

Be it known that I, MILLER REESE HUTCHISON, a citizen of the United States, and a resident of Orange, in the county of Essex and State of New Jersey, have invented a new and Improved Gate and Barrier Control Mechanism, of which the following is a full, clear, and exact description.

This invention relates to gate and barrier control mechanism for use in self-service stores or other establishments, and has reference more particularly to the combination, in a sales or like establishment, of a plurality of barriers for predetermining the course of a customer within the establishment, with means for simultaneously controlling the barriers. The invention also relates to the combination, in a sales establishment, of barriers therein for predetermining the course of a customer, and portal control mechanism for the establishment, with means for simultaneously operating the barriers and the portal control mechanism.

An object of the invention is to provide a simple and efficient mechanism for controlling gates and barriers within a sales or like establishment, by means of which the barriers can be readily rendered inoperative in case of emergency, or for other reasons, which is simple and effective in operation, and which can be inexpensively produced.

A further object of the invention is to provide mechanism of the kind specified, which can be readily controlled from a central point or station, which will be operative at all times, when desired, and which requires but a very simple manipulation for its operation and control.

A still further object of the invention is to provide mechanism of this kind, which, while adapted for use with many different kinds of establishments, is particularly useful in connection with self-service stores.

With these and other objects in view the invention consists in certain novel features of construction, and combinations and arrangements of parts, as will be more fully hereinafter described and pointed out in the claims.

50 In the accompanying drawings—
Figure 1 is a diagrammatic plan view

showing a form of self-service store having my invention incorporated therein;

Figure 2 is a longitudinal fragmentary section of the establishment shown in Figure 1;

Figure 3 is an enlarged partial transverse section on the line 3—3 of Figure 1; and

Figure 4 is a fragmentary enlarged section of the upper part of the construction shown in Figure 3.

Before proceeding to a more detailed explanation of my invention, it should be clearly understood that while I have shown the same, for example, as incorporated in a self-service store, such as that disclosed in my copending application for Letters Patent of the United States, filed June 7, 1922, Serial No. 566,607, the gate and barrier control mechanism may be advantageously employed with other like or different establishments. It will also be understood that while I have illustrated herewith, as one of the barriers controlled by means of my system, a portal control mechanism, such as that disclosed in my copending application for Letters Patent of the United States, filed May 22, 1922, Serial No. 562648, this particular feature of the present system is not an essential one and some other apparatus may be used in its place or it may be entirely dispensed with.

Essentially, my invention contemplates means for controlling a plurality of separated gates, barriers or portal controls in a sales establishment or the like, which barriers predetermine, or partly predetermine, the course of the customers within the establishment, so that, in case of emergency, the barriers or the like may be inoperatively disposed to eliminate the predetermination of the course of the customers and to give them freedom of exit from the establishment or complete freedom of movement within it. Many of the details of construction may be varied in accordance with individual preference or special conditions, without departing from the spirit of the invention.

In establishments of the kind here under discussion, the merchandise is arranged openly on display in suitable merchandise holders or containers, such as shelves or the

like, so that the customer entering passes through the store and selects, from its merchandise holders, the goods which he or she desires to purchase. On leaving the store the purchase is checked up and wrapped, if necessary. The customer then makes payment and leaves the establishment. As will be pointed out more particularly hereinafter, I provide means which not only assist the customer in carrying the selected merchandise through the establishment, but which, at the same time, direct and predetermine his course, so that he must pass practically all of the merchandise on display. This frequently causes the customer to add to his purchase articles which he would not otherwise have selected or which had not occurred to him until he had seen them.

Referring more particularly to the drawings, my self-service store is located in any building of suitable construction, and preferably of elongated form, having side walls 11, a rear wall 12, and the customary store front 13. The store front is provided with an entrance 14, preferably at the center, and having doors or the like. The front also is suitably provided with show-windows 15. I employ a vestibule 16 leading into a lobby or foyer 17. At one side of the lobby I provide a portal, passage through which is controlled by suitable mechanism, such as a pair of turnstiles 18. The lobby is divided from the salesroom 19 of the store by a partition or rail 20 and a counter 21 extending transversely with respect to the rail 20.

At the rear the salesroom 19 is separated from a storeroom 22 by means of a wall or partition 23, having at one side a door 24 connecting the salesroom and the storeroom.

Arranged within the salesroom and extending transversely thereof is a checking counter 25. This is disposed parallel to the counter 21 and rearwardly spaced therefrom. At the ends the counter 25 has forwardly projecting rails 26 and 27. Of these the latter terminates at a point substantially central with respect to the turnstiles 18. The rail 26 extends to a point slightly to the rear of the counter 21. A second counter 28 is located within the salesroom parallel to the counter 25 and rearwardly spaced therefrom. Swinging gates 29 are hung at the ends of the counter 25 and extend to the counter 28 to prevent customers entering between these two counters.

Positioned within the salesroom and extending longitudinally thereof are two parallel merchandise holders 30. These may consist of cabinets, shelves, bins, or any other suitable devices for the purpose. The merchandise holders may be two or more in number, and each at its ends is spaced respectively from the partition 23 and from the counter 28, as is clearly shown in Fig-

ure 1. Between the ends of the merchandise holders 30 and the partition 23 are gates or barriers 31 of any suitable construction, mounted to slide vertically in guides provided for the purpose. These gates, when in normal positions, are lowered, as is shown in Figure 2, and render difficult the passage of customers between the rear ends of the merchandise holders 30 and the partition 23. Between the merchandise holders 30 is arranged an additional or auxiliary merchandise holder 32, likewise consisting of shelves, bins, cabinets, or similar structures. Extending along the side walls of the building are shelves, cabinets, bins, or the like, 33 80 constituting merchandise holders of any suitable type. The last-mentioned merchandise holders 33 extend from the rear wall or partition 23 towards the front of the salesroom. An additional merchandise holder 34 is located at the front of the store across one of the show-windows 15. Near the last-mentioned merchandise holder 34 is a display holder 35, upon which may be arranged fruits, vegetables, and the like. I 90 prefer to associate with the last-mentioned display holder a centrally positioned fountain 36, for purposes of ornamentation and likewise to assist in keeping the perishable merchandise on display in good condition. 95 A further merchandise holder 41 is built into the partition 23 and extends into the storeroom, as is clearly shown in Figure 1.

A gate or barrier 42, similar to the like devices 31, is positioned between the forward end of the merchandise holder 32 and the counter 28.

I provide a track and carrier constructed for use in connection with my store, which consists, for example, of a monorail 40 105 mounted in any suitable manner upon the various supports thereof, such as the merchandise holders and the partition 23. The monorail extends from a point near the forward end of the merchandise holder 33 at 110 the entrance side of the salesroom, along the length thereof, across the door 24, along both sides of the adjacent merchandise holder 30, along the length of the merchandise holder 41, along both sides of the other 115 merchandise holder 30, along the adjacent portion of the partition 23, and along the length of the remaining merchandise holder 33 to a point adjacent the inner end of the merchandise holder 35. The monorail may 120 be of any suitable construction, and, for example, may be similar to that disclosed in my copending application for Letters Patent of the United States, Serial No. 567,179, filed June 9, 1922. I employ carriers in 125 connection with the track system, which may be of any suitable type, and are arranged to travel upon the rail and be propelled by the customer. Preferably they are so constructed that they may be freely re- 130

5 moved from the track and carried by the customer. I have indicated such carriers at 37. Near the entrance to the salesroom is located a carrier receptacle 38, so that each 6 customer, as he enters the salesroom, may take one of the carriers and place it upon the monorail for use as he proceeds through the establishment and selects his merchandise. I also provide suitable mechanism 10 39 for returning the carriers, when the customers are through with them, from the counter 25 to the carrier receptacle 38. This carrier returner may be of any suitable construction, though I prefer to utilize that 15 form of the device which is shown in my patent application above referred to, Serial No. 567,179. Adjacent to the barriers 31 the monorail has movable sections 31^a secured in any suitable manner to the barriers 31, so that they may move with the same. Thus, when the barriers are inoperatively disposed, the monorail sections are likewise displaced and offer no obstruction to the movement of customers at the rear 20 25 ends of the merchandise holders 30.

A gate or barrier 42, similar to the like devices 31, is positioned between the forward end of the merchandise holder 32 and the counter 28.

30 The portal control mechanism, which I prefer to employ with my self-service store, includes two turnstiles 18. It has a base 43, upon which are mounted two spaced vertical posts or columns 44 of cylindrical form. 35 These posts 44 are seated in suitable sockets 45 and have their upper extremities received in openings 46 of a housing 47 secured above the base 43 and forming the top of the portal. Preferably, the housing 47 is 40 mounted under the ceiling of the establishment which the portal serves.

Slidably and rotatably positioned upon each of the posts 44 is a cylindrical hub 48, to which the arms of the turnstiles 18 are 45 secured. Positioned between the posts is a gate or barrier 49 having at its upper corners arcuate extensions 50, which partly embrace the posts and slidably guide the barrier between them. At its lower corners the 50 barrier has brackets 51 for a like purpose. Each hub 48 has a ratchet 52, with which cooperates a spring-pressed dog 53 carried by one of the brackets 51. The dog and ratchet devices control the direction of turning 55 of the turnstiles in the usual manner.

Slidably positioned within each of the posts 44 is a counterweight 54 having at its upper end a reduced part 55 and an ear 56. A flexible connection, such as a cord 57, is 60 connected to the barrier 49 and one of the counterweights passing over a pair of suitable pulleys 58 and 59 provided for the purpose within the housing 47. Pivottally mounted on the shaft of one of the pulleys 65 58 and 59 is a latch 60, the nose of which

engages the reduced part 55 of the corresponding counterweight and serves to hold the same in a normal raised position. A similar latch 61 cooperates with the other counterweight. The two latches are operatively joined by means of a connecting rod 62, so that they will operate in unison. A flexible member, such as a cord 63, is secured to the other counterweight 54 and passes over a pulley 64, upon the shaft of which the latch 61 is pivotally mounted. A flexible member 65 is secured to the end of the connecting rod 62 and passes around a horizontal pulley 66 and out of the housing. The flexible member or cord 65 passes over a pulley 67 and depends to a position near the cashier's cage or station 68 at the end of the counter 25, having at its lower extremity a handle 69 for its manipulation. The cord or cable 63, after leaving the housing and passing around a pulley 63^a, is joined to similar additional cables 70, which pass over pulleys 71 and are connected respectively to the barriers 31 and 42.

The arrangement of the parts is such that in the normal positions of the counterweights 54, the turnstiles 18, the barrier 49, and the gates 31 and 42 are all lowered and, in normal positions, obstructing the movement of the customers in the salesroom. In 90 case of emergency, or for other reasons, all these gates, barriers, and the like, may be inoperatively positioned simultaneously by the attendant at the cashier's counter seizing the handle 69 and pulling downwardly upon the cord or cable 65. When this is done, the latches 60 and 61 are withdrawn from engagement with the counterweights. The latter descend within the hollow posts and, in so doing, pull upon the cables 57, 63 and 70 100 and move all of the barriers attached thereto upwardly. A spring 72 connected to the end of the connecting rod 62 and to the housing serves normally to hold the latches in operative positions until they are released 105 by the action of the attendant. It will be seen that by means of this system, all of the gates and barriers, which predetermine the movements of the customers within the salesroom, can be simultaneously rendered 110 inoperative from a central point or station, when so desired.

I claim:

1. In a self-service store, a plurality of articles of store furniture, said articles being 120 arranged to form a continuous passage through the store, a plurality of carriers arranged to coact with said articles of furniture to form said continuous passage, and means for simultaneously moving said barriers to ineffective position to destroy the continuous nature of the passage to provide paths of exit shorter than usual in case of emergency.

2. In a self-service store, a salesroom hav- 125

ing a portal, a gate associated with said portal and operable only for the ingress of customers, a plurality of articles of store furniture arranged to form a continuous passage 5 through the salesroom away from said portal, a plurality of barriers arranged to contact with said articles of furniture to form said continuous passage, and means for simultaneously moving said gate to a position 10 to allow egress of customers and for moving said barriers to ineffective position to destroy the continuous nature of the passage and to provide paths of exit shorter than usual.

15 3. In a self-service store, a salesroom including a plurality of articles of store furniture spaced to establish alongside the same a plurality of passages to be traversed by customers, a portal having a swing gate operable only for the ingress of customers, a barrier extending from one of said articles of furniture and so disposed as to make closed aisles of a plurality of said passages, and means for simultaneously moving said 20 barrier to ineffective position and moving said gate to a position to permit egress of customers from the salesroom, thereby to establish shortened and unimpeded paths of exit from the salesroom in case of an emergency.

25 4. In a self-service store, a salesroom including a plurality of articles of store furniture spaced to establish alongside the same a plurality of passages to be traversed by customers, a portal having a pivoted gate operable only for the ingress of customers, a barrier extending from one of said articles of furniture and so disposed as to make closed aisles of said plurality of passages, and means operable from a central station 30 for moving said barrier to ineffective position and moving said gate to permit egress of customers from the salesroom, thereby to establish shortened and unimpeded paths of exit from the salesroom in case of an emergency.

35 5. In combination, in a sales establishment, a salesroom having a portal, controlling mechanism associated with said portal and comprising a turnstile, a plurality of articles of store furniture and a barrier within said salesroom for guiding the movement of customers therein relative to a predetermined path, and means for rendering said control mechanism and said barrier ineffective, thereby to provide a shortened and unimpeded path of exit for customers in case of an emergency.

40 6. In combination, in a sales establishment, a salesroom having a portal, controlling mechanism associated with said portal and comprising a turnstile, a plurality of articles of store furniture and a barrier within said salesroom for guiding the movement of customers therein relative to a pre-

determined path, means for normally urging said barrier and said control mechanism to ineffective position, and releasing means for the means last mentioned.

45 7. In combination, in a sales establishment, a salesroom having a portal, controlling mechanism associated with said portal and comprising a turnstile, a plurality of articles of store furniture and a barrier within said salesroom for guiding the movement of customers therein relative to a predetermined path, means for normally urging said barrier and said control mechanism to ineffective position, and releasing means for the means last mentioned and operable 50 from a central station.

55 8. In combination, in a sales establishment, a salesroom having a portal provided with a movable turnstile, a barrier arranged to move with said turnstile, a second barrier within said salesroom, said turnstile and said barriers normally being in effective positions, means connected with said turnstile and said barriers and tending to move the same into ineffective positions, means for holding said last-mentioned means inoperative, and means for releasing said last-mentioned means.

60 9. In combination, in a sales establishment, a salesroom having a portal, control mechanism arranged at said portal and comprising a turnstile and a barrier adapted to move in unison, a second barrier within said salesroom, a counterweight tending to move said turnstile and said barriers into 65 ineffective positions, a latch for holding said counterweight inoperative, and means for releasing said latch from a distant point.

65 10. In combination, in a sales establishment, a salesroom having a portal, control mechanism arranged at said portal and comprising a turnstile and a barrier mounted to be moved vertically into ineffective positions, barriers within said salesroom and serving to regulate the movement of customers therein, said last-mentioned barriers being vertically movable into ineffective positions, and common means for releasably holding said turnstile and said barriers in predetermined positions.

70 11. In combination, in a sales establishment, a salesroom having a portal, control mechanism arranged at said portal and comprising a turnstile and a barrier mounted to be moved vertically into ineffective positions, barriers within said salesroom and serving to regulate the movement of customers therein, said last-mentioned barriers being vertically movable into ineffective positions, means tending to raise said turnstile 75 and said barriers into ineffective positions, and means for controlling said last-mentioned means from a central point or station.

75 12. In a combination, in a sales establishment, a salesroom having a portal, control 80

mechanism arranged at said portal and comprising a turnstile and a barrier vertically movable in unison, a plurality of barriers arranged within said salesroom and vertically movable, counterweights tending to move said turnstile and said barriers into ineffective positions, flexible members connecting said counterweights and said turnstile and barriers, means for holding said counterweights inoperative, and means for releasing said last-mentioned means from a central point or station. , 10

MILLER REESE HUTCHISON.
